UNITED STATES PATENT OFFICE.

NICKOLA KIEFFER, OF SAN ANTONIO, TEXAS.

BITTERS.

SPECIFICATION forming part of Letters Patent No. 308,900, dated December 9, 1884.

Application filed June 23, 1884. (Specimens.)

To all whom it may concern:

Be it known that I, NICKOLA KIEFFER, a citizen of the United States, residing at San Antonio, in the county of Bexar and State of Texas, have invented a new and healthy composition of matter to be used as a tonic, and to be known as the "Improved Bitters," of which the following is a specification.

My composition consists of the following ingredients, combined in the proportions stated, viz: Cologne spirits, fifty gallons; Ceylon cinnamon-bark, (Cinnamomum Zeylanicum,) two ounces; orange-peel. (Citrus aurantium,) four ounces; galanga-root, (Maranta galanga,) four ounces; zedoary-root, (Curcuma zedoaria,) two ounces; cloves, (Caryophyllus aromaticus,) five ounces; star aniseed, (Illicium anisatum,) two ounces; coriander, (Coriandrum sativum,) eight ounces; Roman chamomile, (Anthemis nobilis,) two ounces; cassia-buds, (Cinnamomum cassia,) four ounces; juniper-berries, (Juniperus communis,) eight ounces; gentian-root, (Gentiana lutea,) four ounces; wormwood, (Artemisia absinthium,) nine ounces; peppermint herb,

(Mentha piperita,) two ounces; calamus-root, 25 (Acorus calamus,) thirteen ounces; elder-flowers, (Sambucus Canadensis,) six ounces; lavender-flowers, (Lavandula vera,) two ounces; cardamom-seed, (Elettaria cardamomum,) two ounces; mace, (Myristica fragrans,) four ounces. 30 The doses to be taken of the stomach-bitters are one table-spoonful before each meal.

What I claim, and desire to secure by Letters Patent of the United States, is—

The herein-described composition of matter 35 to be used as a stomach-bitters, consisting of Cologne-spirits, Ceylon cinnamon, orange-peel, galanga-root, zedoary-root, cloves, star aniseed, coriander, Roman chamomile-flowers, cassia-buds, juniper-berries, gentian-root, 40 wormwood, peppermint herb, calamus-root, elder-flowers, lavender-flowers, cardamom-seed, and mace, in the proportions specified.

NICKOLA KIEFFER.
